DELINTING DEVICE FOR DRYING TUMBLERS

Original Filed Sept. 10, 1920

2 Sheets-Sheet 2

UNITED STATES PATENT OFFICE.

JAMES H. TAYLOR, OF NEW YORK, N. Y., ASSIGNOR TO THE AMERICAN LAUNDRY MACHINERY COMPANY, OF CINCINNATI, OHIO, A CORPORATION OF OHIO.

DELINTING DEVICE FOR DRYING TUMBLERS.

Application filed September 10, 1920, Serial No. 409,449. Renewed January 11, 1923.

To all whom it may concern:

Be it known that I, JAMES H. TAYLOR, a citizen of the United States, residing at New York, in the county of New York and State of New York, have invented certain new and useful Improvements in Delinting Devices for Drying Tumblers, of which the following is a specification.

This invention relates to the art of laundry machines, more especially to the class of drying apparatus, as for instance, the type known as drying tumblers, in which I have devised a means for removing lint from the air after its passage through the drying chamber.

The drying tumbler comprises in general an air and fan chamber, a heating chamber, and a drying chamber with means for forcing a current of air through the said several chambers for the purpose of drying materials in the drying chamber. Air is sucked in by the fan from the outside, and after being warmed by passing through the heating chamber is forced through the drying chamber and then back to the air chamber. From this point the air will be wholly re-circulated over the same path or may be partially expelled from the machine and only part of it recirculated through the machine. Either of these two methods may be followed in the process of drying the materials contained within the drying chamber. Then when it is desired to cool the materials within the drying chamber preparatory to their removal, the heating chamber can be excluded from the circuit of air through the machine, so that the fresh air which is sucked into the machine casing by the fan is forced directly through the drying chamber and thence back to the air chamber, from which point it is wholly expelled from the machine casing and replaced by a fresh supply from the outside atmosphere. The circulation of air in the different manners just referred to is made possible by means of dampers which control communication between the several chambers, as will appear later on in the description.

In all the manners of operation just referred to it has been found that considerable lint is picked up by the air in its passage through the drying chamber, which lint, if not filtered from the air, would be recircu-

lated through the machine, and would also be drawn into the fan. Then upon forcing part or all of the lint-laden air to the outside atmosphere considerable annoyance would be caused to employés who are engaged in work in the room where such a drying tumbler is situated. Thus it is deemed highly desirable to remove the lint from the air under all circumstances.

The object of my invention is therefore to remove the lint from the air after its passage through the drying chamber by means of a perforate screen through which the air is caused to pass in its return to the air chamber.

I have also provided means whereby this lint collecting screen will pass from a point inside the machine casing to a point outside of the casing where the lint can be removed from the screen member.

Another object of my invention consists in the provision of means for the removal of lint from the screen member by the use of brushes wiping against the screen and depositing the lint in a fluid body which carries it off to the point of discharge.

My invention comprises also the provision of automatic means connected with the fan for moving the perforate lint collector into and out of the machine casing, and also for the operation of the brushes which remove the lint from the collector.

Other forms of structure will suggest themselves for embodying this invention, but the preferred form will be understood from the following description and claims when considered in connection with the accompanying drawings.

Fig. 1 is a vertical transverse section through the machine casing; Fig. 2 is a view of the machine casing partly in full and partly in section showing the gear connection between the fan and operating means for the lint collector, and also the arrangement of the lint collector itself; Fig. 3 is a section in the plane of a line *c-c*, Fig. 2, showing the arrangement of the endless lint collector and the brushes; Fig. 4 is a detail plan view of the structure of the endless lint collector; Fig. 5 is another detail view of the structure of the lint collector in transverse section; Fig. 6 is a sectional view in the plane *b-b*, of Fig. 2, showing the

5 manner of mounting the rotary brushes; Fig. 7 is a detail view of the water main in the fluid container; and Fig. 8 is a vertical section of the two-way valve taken in the 10 plane a—a of Fig. 2.

15 The lower part of the machine casing 1 constitutes a heating chamber 2, while the upper part of the casing is divided into a fan and air chamber 3 and a drying chamber 4 in which is located and mounted the foraminous tumbler 4. The air chamber is further partitioned off into a fresh air chamber 5 which has communication with the main part of the air chamber 3 through 20 passageway 6, and also with the drying chamber through a passage-way which is controlled by damper 7. The passage-way 6 is also controlled by this same damper 7 which is hingedly mounted on the shaft 8. 25 The fan casing 9 is located within the main air chamber 3 and incloses the fan 10 which operates upon its shaft 11. Communication is also provided between the air and fan chamber 3 and the heating chamber 2, which 30 communication is controlled by damper 12 hingedly mounted by means of shaft 13. The damper 14 on the hingedly mounted shaft 15, which has an I-beam support 16, controls the passage-way 17 which allows 35 communication between the heating chamber 2 and the drying chamber which incloses the foraminous tumbler 4. A stop 18 is further provided upon the partition wall 19 for the damper 7, while a shoulder or stop 40 is provided for the damper 14 at the end of the same partition wall 19. As will be seen from Fig. 1, the partition wall 21, which is a continuation of the partition 22, is spaced from the partition wall 19 so as to 45 provide the fresh air chamber 5. The partition wall 22 has the proper curvature to accommodate the cylindrical form of the foraminous tumbler 4. The damper 12 controls also the outlet 24 through which air may be forced from the air and fan chamber 3 to the outside atmosphere.

50 As will be seen in Fig. 1, the partition wall 22 is bent back to form a wall 25 which is substantially parallel with the top part 55 of the main casing wall. An aperture 26 of the main casing wall 25 across 27 is provided in the partition wall 25 across the full extent of the machine, the air from the drying chamber being forced through this opening on its return to the air chamber. It is at this point that I provide a lint 60 collecting means, the detailed description of which will follow later.

65 The heating chamber, which is provided with doors 28 and 29, incloses the heating coils 30 which are mounted upon the truck 31 and are provided also with baffle plates 32.

70 Referring now to the drying chamber, it will be seen from Fig. 1 that a door 33 is provided in the foraminous cylinder 4

75 through which access may be had to the materials contained therein upon opening door 34 which is hingedly mounted upon the main casing 1. Baffle plates 35 are also provided within the tumbler for a well known purpose.

80 Brief reference will now be made to the operation of the device as described up to this point. When the dampers 7, 12 and 14 occupy the positions as shown in Fig. 1, 75 fresh outside air is sucked into the machine by the fan 10 and is forced through the heating coils where it will follow a circuitous route because of the baffle plates 32, and thence through the passage-way 17 to the 85 drying chamber, from which point it will pass through the air passage between walls 25 and 26. This air which has collected more or less lint from the materials contained within the drying tumbler will now 90 be filtered through the screen 34' which extends over the opening 27 and the clean air will be returned to the air and fan chamber 3. This air will now be partly expelled 95 from the machine casing through the outlet 90 100 105 110 115 120 125 130 135 140 145 150 155 160 165 170 175 180 185 190 195 200 205 210 215 220 225 230 235 gear and pinion connections from the fan shaft 11. The screen belt is so arranged as to have two parallel stretches, one extending through the inside of the machine casing, 5 while the other extends on the outside. This will be better understood from Fig. 3 in which the lower stretch of the endless screen member is shown as extending through the walls of the machine casing, 10 while the upper stretch of the belt passes over a fluid tank which is arranged on the top of the machine casing. This tank 36 is provided with a water supply pipe 37 having apertures 38, and also with an overflow 15 outlet 39 and drain outlet 40. The overflow and drain outlets 39 and 40, respectively, as will be seen from Fig. 2, have a common discharge pipe 41, shown better in Fig. 8. By means of a two-way valve 42 under control 20 of handle 43, either of the outlets 39 or 40 may be brought into communication with the discharge pipe 41. A constant supply of water or other suitable fluid is obtained through pipe 37 and the overflow will be 25 taken care of by outlet 39. When it is desired, however, to clean the tank, the valve 42 will be so arranged as to allow communication between the drain outlet 40 and the discharge pipe 41, so that the tank 36 may 30 be flushed.

Rotary brushes 44 are mounted on their shafts 45 on the walls of the tank 36 and the upper stretch of the endless lint collector is so arranged that these brushes will 35 have a proper wiping engagement with the under face of the lint collector at this point. The shafts of these brushes are secured in position at one end by means of the bearings 46 hinged at 47. Thumb screws 47^a 40 which may be mounted in any suitable manner lock the bearings 46 in closed position. By means of this detachable mounting it is possible to remove the brushes whenever 45 desired for the purpose of cleaning, the other ends of these shafts being mounted in fixed bearings 48 on the wall of the tank.

The shafts of the brushes extend at one end beyond the casing wall, as shown in Fig. 3, and these ends are provided with pulleys 48' which receive operation from the shafts 49 and 50 of the sprocket members by means 50 of the belt connections 51. The sprockets 52, 53, which have a clockwise movement, transmit to the brushes a counter-clockwise movement, as a result of which these brushes will tend to move the fluid in the tank toward the outlets 39 and 40. The sprocket shafts 49 and 50 are suitably mounted in bearings 54 and 55 upon the outside walls of the casing and receive their operation through bevel gear 56' mounted upon shaft 56, which gear 56' meshes with a bevel gear 57, which is in turn mounted upon the same shaft with gear 58. The train of gears and pinions 59, 60, 61, 62 and 63 provide a drive

connection between gear 58 and the shaft 11 of the fan upon which shaft is mounted gear 63. A pair of sprockets, one being shown at 64 are mounted on the opposite wall of the casing and serve as idlers for the 70 endless screen belt. Thus it will be seen that drive connection is had between the fan shaft and the shafts of sprockets and also the rotary brushes which have pulley connection with the shafts of the sprocket members. I do not limit myself to any particular gear ratio between the shaft 11 and the shaft 45, but it is understood that any ratio may be used to give the proper speed for 75 operation of the endless web or belt 34'. 80

The side edge portions of the perforate belt member 34' are secured to the chain member 66, which, as will be seen from Fig. 4, has openings for engagement with the teeth upon the sprockets 52, 53. These chain 85 members have connecting ears 67 upon which the side edge portions of the screen member 34 are mounted, the screen being held in this position by means of clamping blocks 68 and rivets 69 which pass through 90 the blocks 68 and the ears 67. Along the other face of each of the chain members 66 there extends a felt strip 69' which is also secured in this arrangement by means of the same rivets 69. The edge portions along 95 the opening 27 serve as tracks for the belt and are reinforced by means of angle bars 70. As seen in Fig. 3, the two parts of the partition 25 along the aperture 27 extend beyond the casing walls and are curved 100 downwardly as indicated at 71, in line with the track portions, so as to facilitate the entrance of the screen belt into the openings in the casing wall. As shown at 72, in Fig. 3, the outer marginal portions of the felt 105 strips 69' will assume the position indicated by dotted lines in Fig. 5 during the time of the engagement of the sprocket teeth in the holes in the chain member 66. During the time, however, when the endless belt is passing through the machine casing, the felt strips 69' will assume the position indicated by full lines in Fig. 5. 110

By virtue of the particular location and arrangement of the lint collector, as best 115 illustrated in Fig. 1, between the fan chamber and the drying chamber, the suction caused by the fan tends to hold or seal the lower stretch of the endless belt upon its track and in this way produce a more efficient operation, since it will be impossible for any particles of lint to pass through the opening 27 without being filtered through the foraminous member 34'; that is to say, the felt members 69 will be caused by suction 120 to closely adhere to the track and in this way seal or prevent any opening under the belt member through which any particles of lint might otherwise pass from the drying chamber to the air chamber. 125 130

With the above construction it will be seen that only one stretch of the lint collector will be exposed to the lint-laden air at any one time, and that fresh unexposed portions of the lint collector are being constantly substituted for the preceding portion through which the lint-laden air has passed. As a result of this arrangement a very large aggregate surface area is brought to the point of exposure to the lint-laden air. Furthermore, by the use of the rotary brushes lint is effectively removed from the foraminous member and deposited in the circulating fluid to be discharged. That portion of the screen is then returned to the place of exposure within the machine in a clean fresh condition.

Other advantages resulting from applicant's device will suggest themselves to those who are familiar with the art to which this invention relates.

What I claim is:

1. In a drying machine, the combination of a machine casing, an air and fan chamber, a heating chamber, a drying chamber, means for circulating air through said several chambers, a non-liquid lint collecting device arranged to be moved into and out of the machine and across the path of the air after its passage through the drying chamber, and means for operating said device.

2. In a drying machine, the combination of a machine casing, an air and fan chamber, a heating chamber, a drying chamber, means for circulating air through said several chambers, a lint collector arranged to be moved into and out of the machine casing and across the path of the air after its passage through the drying chamber, means for operating said lint collector, and means arranged outside of said casing for removing the lint from said collector.

3. In a drying machine, the combination of a casing, an air and fan chamber, a heating chamber, a drying chamber, means for causing the flow of air through said chambers, an endless lint collector for collecting lint from the air after its passage through the drying chamber, said collector being arranged with one portion in the path of the active current of air and another portion shielded from contact with any air circulated within the casing, and means for operating said lint collector to move the shielded portions thereof into the path of the active current of air.

4. In a drying machine, the combination of a casing, an air and fan chamber, a heating chamber, a drying chamber, means for causing the flow of air through said chambers, an endless lint collector for collecting lint from the air after its passage through the drying chamber, said collector being arranged with one portion in the path of the active current of air and another

portion shielded from contact with any air circulated within the casing, means for operating said lint collector to move the shielded portions thereof into the path of the active current of air, and means outside of the active current of air for removing the lint from said collector.

5. In a drying machine, the combination of a casing, an air and fan chamber, a heating chamber, a drying chamber, means for causing the flow of air through said several chambers, a lint collector for collecting the lint from the air after its passage through the drying chamber, said collector having one portion in the path of the active air current and another portion shielded from any air circulated within the casing, a liquid container in proximity to said collector and outside of the active air current, and means for removing lint from the collector and depositing it in the liquid in said container.

6. In a drying machine, the combination of a casing, an air and fan chamber, a heating chamber, a drying chamber, means for producing flow of air through said chambers, and a non-liquid lint collecting means for collecting lint from the air after its passage through the drying chamber, said means having one portion in the path of the active air current and another portion shielded from contact with any air circulated within the casing, and means for automatically and successively presenting fresh portions of said means for exposure to the air coming from the drying chamber.

7. In a drying machine, the combination of a casing, an air and fan chamber, a heating chamber, a drying chamber, means for causing flow of air through said chamber, a perforate medium movable into and out of said casing for collecting lint from the air after its passage through the drying chamber, and means for automatically and successively presenting fresh portions of said medium for and withdrawing the same from exposure to the air coming from the drying chamber.

8. In a drying machine, the combination of a casing, an air and fan chamber, a heating chamber, a drying chamber, means for causing the flow of air through said chambers, a medium for collecting lint from the air after its passage through said drying chamber, means in said casing for preventing exposure of more than a portion of said medium at a time in the path of the air current, means for automatically removing successive portions of said medium to a point away from the point of exposure and out of any contact with any air circulated in the casing, and means for automatically removing the lint from said exposed medium and returning the same medium to position for further exposure.

9. In a drying machine, the combination of a casing, an air and fan chamber, a heating chamber, a drying chamber, means for causing the flow of air through said chambers, a medium for collecting lint from the air after its passage through said drying chamber, means in said casing for preventing exposure of more than a portion of said medium at a time in the path of the air current, means for automatically removing successive portions of said medium to a point away from the point of exposure and out of any contact with any air circulated in the casing, means for automatically removing the lint from said exposed medium and returning the same medium to position for further exposure, and means for removing the lint from said medium.
10. In a drying machine, the combination of a machine casing, an air and fan chamber, a heating chamber, a drying chamber, means for circulating air through said several chambers, a lint collector, said machine casing being provided with a seat for said lint collector as it is exposed to the lint-laden air, means for controlling the path of air so that it will be directed against said collector after its passage through said drying chamber, said collector being so arranged on said seat and being responsive to the suction of said air circulating means so that such suction will tend to hold said collector upon said seat.
11. In a drying machine, the combination of a casing, an air and fan chamber, a heating chamber, a drying chamber, means for causing the flow of air through said chambers, the machine being provided with an opening through which the air flows after passing through the drying chamber, a web-like lint collecting device movable across said opening for removing the lint from the air, and sealing means for said opening carried by said device.
12. In a drying machine, the combination of a machine casing, an air and fan chamber, a heating chamber, a drying chamber, means for circulating air through said several chambers, a lint collector arranged in the path of the air after its passage through said drying chamber, a fluid body arranged in proximity to said collector, a brush arranged for wiping contact with said collector, and means for operating said brush to remove the lint from said collector and deposit it in said fluid.
13. In a drying machine, the combination of a machine casing, an air and fan chamber, a heating chamber, a drying chamber, means for circulating air through said several chambers, a lint collector arranged in the path of the air after its passage through said drying chamber, a circulating fluid body arranged in proximity to said collector, a brush for removing the lint from said collector and depositing the same in said fluid body, and means for operating said brush.
14. In a lint collecting device, the combination of a perforate lint collecting body, a driving sprocket, a sprocket chain for engagement with the driving sprocket, ears projecting from said chain, blocks securing the marginal portions of said collecting body to said ears, and a wiper felt secured to the opposite faces of said ears, that portion of said felt covering the chain proper being free for movement away from said chain to permit engagement of the sprocket teeth with said sprocket chain.
15. In a drying machine, the combination of a machine casing, an air and fan chamber, a heating chamber, a drying chamber, means for circulating air through said several chambers, a partition wall extending from said drying chamber to the side wall of said casing and forming a restricted area with the top walls of said casing, said partition wall being provided with a longitudinal aperture at a point above the fan and air chamber, the marginal portions of said aperture being provided with track portions, said casing being provided with apertures in its walls at the opposite ends of said first named longitudinal aperture, thereby permitting the travel of a foraminous lint collecting member along said tracks and through said casing.
16. In a lint collecting device, the combination of a fluid container, one wall of said fluid container being provided with a bearing for the reception of a journal, the opposite wall having a semi-circular notch to receive the other end of a journal, a lock member hingedly mounted on a horizontal axis upon the side of said notch, the underside of said lock member having a semi-circular depression supplemental to that in said side wall, and means for detachably securing the other end of said locking member so as to provide a journal bearing for a brush member.
17. In a drying machine, the combination of a machine casing, an air and fan chamber, a heating chamber, a drying chamber, an endless perforate body for collecting lint from the air after its passage through the drying chamber, means for circulating air through said several chambers and through said perforate body after its passage through the drying chamber, said perforate body being so arranged as to have the air pass only from the inside outwardly through one stretch of said endless body.
18. In a drying machine, the combination of a machine casing, an air and fan chamber, a heating chamber, a drying chamber, a perforate medium for collecting lint from the air after its passage through the drying chamber, means for moving said medium into and out of said casing, and means for

circulating air after its passage through the drying chamber through said several chambers and through said medium.

19. In a drying machine, the combination of machine casing, an air and fan chamber, a heating chamber, a drying chamber, an endless perforate body for collecting lint from the air after its passage through the drying chamber, means for circulating air after its passage through the drying chamber through said several chambers and through said perforate body, said perforate body being so arranged as to have the air pass only from the inside outwardly through one stretch of said endless body, and means located between the stretches of the said endless body and at a point removed from the path of air for removing the lint therefrom.

20. A drying machine including a drying chamber, and a lint collector therefor, comprising a foraminous web member, means for directing the air coming from said drying chamber through said member, and in only one direction with respect to said member and means for moving said member to present fresh surfaces thereof to the circulating air.

21. A drying machine including a drying chamber, and a line collector therefor, comprising a foraminous web member, means chamber, and a lint collector therefor, coming chamber through said member, and in only one direction with respect to said member, means for moving said member to present fresh surfaces thereof to the circulating air, and means outside of the air current for removing the lint therefrom.

22. A drying machine including a drying chamber, and a lint collector therefor, com-

prising an endless foraminous member, 40 means for causing the air coming from said chamber to flow through said foraminous member, and in only one direction with respect to said member and means for so moving said endless member as to continuously 45 present fresh surfaces to the air stream.

23. A drying machine including a drying chamber, and a lint collector therefor, comprising an endless foraminous member, 50 means for causing the air coming from said chamber to flow through said foraminous member, and in only one direction with respect to said member, means for so moving said endless member as to continuously present fresh surfaces to the air stream, and 55 means for removing the lint therefrom.

24. A drying machine including a drying chamber, and a lint collector therefor, comprising an endless foraminous member movable in an endless path, means for delivering 60 the air coming from said drying chamber to the inner surface of said endless member and causing the same to flow outwardly therefrom, and means for shielding a portion of said member from the air current.

25. A drying machine including a drying chamber, and a lint collector therefor, comprising an endless foraminous member movable in an endless path, means for delivering the air coming from said drying chamber to 70 the inner surface of said endless member and causing the same to flow outwardly therefrom, means for shielding a portion of said member from the air current, and means for removing the lint from the inner surface of 75 said member.

In testimony whereof I affix my signature.
JAMES H. TAYLOR.

circulating air after its passage through the drying chamber through said several chambers and through said medium.

19. In a drying machine, the combination of machine casing, an air and fan chamber, a heating chamber, a drying chamber, an endless perforate body for collecting lint from the air after its passage through the drying chamber, means for circulating air after its passage through the drying chamber through said several chambers and through said perforate body, said perforate body being so arranged as to have the air pass only from the inside outwardly through one stretch of said endless body, and means located between the stretches of the said endless body and at a point removed from the path of air for removing the lint therefrom.

20. A drying machine including a drying chamber, and a lint collector therefor, comprising a foraminous web member, means for directing the air coming from said drying chamber through said member, and in only one direction with respect to said member and means for moving said member to present fresh surfaces thereof to the circulating air.

21. A drying machine including a drying chamber, and a line collector therefor, comprising a foraminous web member, means chamber, and a lint collector therefor, coming chamber through said member, and in only one direction with respect to said member, means for moving said member to present fresh surfaces thereof to the circulating air, and means outside of the air current for removing the lint therefrom.

22. A drying machine including a drying chamber, and a lint collector therefor, com-

pprising an endless foraminous member, means for causing the air coming from said chamber to flow through said foraminous member, and in only one direction with respect to said member and means for so moving said endless member as to continuously present fresh surfaces to the air stream.

23. A drying machine including a drying chamber, and a lint collector therefor, comprising an endless foraminous member, means for causing the air coming from said chamber to flow through said foraminous member, and in only one direction with respect to said member, means for so moving said endless member as to continuously present fresh surfaces to the air stream, and means for removing the lint therefrom.

24. A drying machine including a drying chamber, and a lint collector therefor, comprising an endless foraminous member movable in an endless path, means for delivering the air coming from said drying chamber to the inner surface of said endless member and causing the same to flow outwardly therefrom, and means for shielding a portion of said member from the air current.

25. A drying machine including a drying chamber, and a lint collector therefor, comprising an endless foraminous member movable in an endless path, means for delivering the air coming from said drying chamber to the inner surface of said endless member and causing the same to flow outwardly therefrom, means for shielding a portion of said member from the air current, and means for removing the lint from the inner surface of said member.

In testimony whereof I affix my signature.
JAMES H. TAYLOR.

Certificate of Correction.

It is hereby certified that in Letters Patent No. 1,522,553, granted January 13, 1925, upon the application of James H. Taylor, of New York, N. Y., for an improvement in "Delinting Devices for Drying Tumblers," errors appear in the printed specification requiring correction as follows: Page 6, line 29, claim 21, for the word "line" read *lint*; same page and claim, lines 31 and 32, strike out the words "chamber, and a lint collector therefor, coming" and insert instead *for directing the air coming from said drying*; and that the said Letters Patent should be read with these corrections therein that the same may conform to the record of the case in the Patent Office.

Signed and sealed this 3d day of March, A. D. 1925.

[SEAL.]

KARL FENNING,
Acting Commissioner of Patents.
